(**) Term: **14 Years**

Primary Examiner—Louis S. Zarfas

Assistant Examiner—Gregory Andoll

(74) Attorney, Agent, or Firm—Sheldon & Mak; Denton L. Anderson

(21) Appl. No.: **29/168,086**

(57) **CLAIM**

(22) Filed: **Sep. 25, 2002**

The ornamental design for a jar cover, as shown and described.

(51) LOC (7) Cl. **09-07**

DESCRIPTION

(52) U.S. Cl. **D9/452**; D9/454; D9/435
(58) Field of Search D9/434, 452, 454,
D9/435, 447; 220/200, 288; 215/200, 356,
230

FIG. 1 is a perspective view of the jar cover of the invention; FIG. 2 is a side view of the jar cover illustrated in FIG. 1; FIG. 3 is a top view of the jar cover illustrated in FIG. 1; FIG. 4 is a bottom view of the jar cover illustrated in FIG. 1; and,

FIG. 5 is a cross-sectional view of the jar cover illustrated in FIG. 3, taken along line 5—5.

1 Claim, 2 Drawing Sheets
